UNITED STATES PATENT OFFICE

JOHN KIRGAN, OF EASTON, PENNSYLVANIA, ASSIGNOR TO INGERSOLL-RAND COMPANY, OF JERSEY CITY, NEW JERSEY, A CORPORATION OF NEW JERSEY

PUMP SEAL

Application filed May 24, 1929. Serial No. 365,617.

This invention relates to an apparatus for condensing steam or other gases and more particularly to a means for conducting air leakage from a condensate pump actuating element to an air removing device for the 5 purpose of preventing air at atmospheric pressure entering the condenser system through the pump actuating element stuffing box and mingling with the condensate in the condensate pump.

Such leakage is undesirable particularly in a steam condenser as it tends to decrease the operating efficiency of the boiler and to impair the condensing efficiency of the 15 condenser owing to the reduction of the vacuum in the condensing system.

An object of the invention is to prevent such air leakage. A further object of the invention is to permit a comparatively loose 20 pump seal, thereby reducing the power loss and wear of parts due to friction. Other objects of the invention are obvious or will be pointed out hereinafter.

A preferred embodiment of the invention 25 by which these objects may be attained is illustrated in the accompanying drawing, in which, similar numerals refer to similar parts;

Figure 1 is a side elevation of a steam condenser installation with parts of the bottom of the condenser, condensate outlet, air outlet and condensate pump actuating element broken away and shown in section.

Figure 2 is an oblique sectional view of an 30 intermediate stuffing box gland for the condensate pump shaft.

Figure 1 shows a surface condenser 1 in which vapor coming from a suitable source such as an engine (not shown) is condensed 35 and whence condensate flows through the condensate outlet 3, through conduit 4 into a condensate pump 5 and is returned through a conduit (not shown) to the boiler (not shown). An air removal device 7 of any desired type is connected by a conduit 8 to the air outlet 22, which connects with the condensate outlet 3. Condensate pump 5 is driven by a pump actuating element such as a shaft 9 which is rotated by a motor or 40 other suitable power device 10 and supported

in bearings 11. Surrounding the shaft at the place where it enters the condensate pump casing 14 is a driving sleeve 12 which rotates with the shaft in a stuffing box 23, in which a plurality of packing rings 13 and an intermediate drainage gland 2 are held in position by a packing gland 15. The drainage gland 2 which may be placed midway of the stuffing box is shown in more detail in Figure 2 and may be built up of two sections of identical construction. Each of these sections consists of one-half of a circular band which is grooved for the greater part of its width on its inside and outside surfaces as at 30 and 31 respectively, leaving 55 two outside rings 16 connected by a web 17 which is perforated by a plurality of holes 18.

Owing to the high vacuum maintained at the suction chamber 32, air tends to pass along the shaft 9 and into the pump 5. Such air 60 is at atmospheric pressure and leaks along the surface of the driving sleeve 12 through the packing rings 13 until it reaches the gland 2. The air is drawn up to the air removal device 7 through a port 19 drilled through the condensate pump casing 14 and connects with the cut-out portion 31 of the outer surface of the drainage gland 2. A suitable pipe 21 is fitted to the port 19 and connects with a port 20 drilled in the casing of the condensate outlet 3 at a point which would be 65 higher than the normal level of the condensate and close to the air outlet 22.

The leakage air which reaches the inside 70 surface 30 of gland 2, is drawn through the 75 perforations 18 by the suction of the air removal devices 7 so that the condensate pump is effectively sealed from air leakage at this point. Pump 5 as shown in this instance is 80 of the double opposed inlet type and accordingly similar stuffing boxes are provided at 85 both ends of the shaft 9. Pipe 33 is arranged to connect the stuffing box at the left side of the pump 5 (Figure 1) and in its functions 90 is similar to pipe 21.

I claim:

1. In a vapor condensing apparatus, a condenser, a condensate pump, an air removal device, an actuating element for the condensate pump, and means for conducting air leak- 100

age from the pump actuating element to the air removal device.

5 2. In a vapor condensing apparatus, a condenser, a condensate pump, an air removal device, a pump actuating element for the condensate pump, means for packing the pump actuating element, and means to conduct air leakage from said packing means to the air removal device.

10 3. In a vapor condensing apparatus, a condenser, a condensate pump, an air removal device, an actuating element for the condensate pump having an air leakage path, and means for connecting the air removal device 15 to the air leakage path in the pump actuating element.

20 4. In a vapor condensing apparatus, a condenser, a condensate pump, an air removal device, an actuating element for the condensate pump provided with a packing chamber, a packing gland providing an open space in the packing chamber of the pump actuating element, and means to conduct leakage air from said gland to the air removal device.

25 5. In a vapor condensing apparatus, a condenser, a condensate pump, an air removal device, an actuating element for the condensate pump, and a packing gland with communication between its inner and outer surfaces whereby leakage air may be conducted from the pump actuating element to the air removal device.

In testimony whereof I have signed this specification.
